UNITED STATES PATENT OFFICE.

AURICE C. CLARK, OF PROVIDENCE, RHODE ISLAND, ASSIGNOR TO MAURICE C. CLARK COMPANY, OF PROVIDENCE, RHODE ISLAND, A CORPORATION OF RHODE ISLAND.

RUBBER FOOTWEAR.

980,173.

Specification of Letters Patent. Patented Dec. 27, 1910.

Application filed May 28, 1908. Serial No. 435,408.

To all whom it may concern:

Be it known that I, MAURICE C. CLARK, a citizen of the United States, residing at Providence, in the county of Providence and 5 State of Rhode Island, have invented certain new and useful Improvements in Rubber Footwear, of which the following is a specification, reference being had to the drawings accompanying and forming part 10 of the same.

This invention relates to the construction of vulcanized rubber soles, whereby they can be readily and easily attached to the leather shoe without the aid of cement, nails, 15 or sewing, and can be as readily and easily removed by the wearer when desired, as in the case of the ordinary rubber overshoe. The improvements comprising the present invention are also applicable to the types 20 of overshoe commonly known as "foot-holds", "sandals", etc.

Briefly stated, the chief object of the invention is to provide simple, inexpensive, and thoroughly effective means for securing 25 a so-called "invisible sole", "foot-hold", or other style of rubber footwear on the wearer's shoe without the use of a heel-strap or counter, at the same time permitting easy and instant removal or detachment by the wearer.

30 Of the various embodiments of which my invention is capable, I have selected for illustration and specific description herein the forms which at the present time I believe exemplify the best mode of applying the invention. Even in the forms just referred to, however, the details of construction can be 35 varied widely without departure from the spirit and scope of the invention as defined by the appended claim.

40 Referring now to the annexed drawings, Figure 1 shows in longitudinal section one form of the invention, attached to a leather shoe, as worn. Fig. 2 is an enlarged cross-section, taken substantially on line II-II 45 of Fig. 1, showing the rubber clenched to the sole of the leather shoe. Fig. 3 is bottom plan view of the rubber, removed from the leather shoe. Fig. 4 is a side view of the same, and Fig. 5 is a cross section substantially on line V-V of Fig. 4, and showing also a different mode of attaching the flange or clenching member to the sole portion of the overshoe. Fig. 6 is a similar cross section, with the clenching flange attached to 55 the sole portion in the same manner as in

Fig. 5, and showing the rubber provided with a cord in the clenching flange. Fig. 7 is a detail perspective view of the member of the fastening means which is attached positively to the rubber sole, and Fig. 8 is 60 a similar view of the member which is attached positively to the leather shoe.

Referring now to the drawings in detail, 1 indicates the rubber sole proper, of the article. 65

2 is the upper or flange-portion, which, joined with the cloth strip 3, forms the flange for clenching the sole 1 to the sole of the leather shoe, as clearly shown in Figs. 1 and 2. As is customary in the construction 70 of rubber footwear, the article is provided with a cloth insole, indicated by 4, extending preferably to the point indicated at 5, Fig. 3.

6, Fig. 5, indicates a suitable filling sole. 75

As so far described, the article is constructed of materials usually employed in the manufacture of rubber footwear. Unlike the ordinary overshoe, however, the cloth insole and the filling sole do not extend entirely over the shank, but are substantially coextensive with the sole-portion only and terminate preferably at the point indicated by the dotted line 5, Fig. 3. The remaining portion of the shank is formed of 80 sheets or layers of elastic rubber, and embedded therein is a stout cloth stay 7, folded to form a loop as clearly shown in Figs. 1, 3 and 4. Linked in this loop is a fastening member 8, provided with a tongue 9 extending forwardly into the open center of the member, and also provided with a rearwardly extending and downwardly bent finger piece 10 for convenient grasp by the finger and thumb in fastening and unfastening 90 the sole, as explained hereinafter.

The leather shoe with which the article is to be worn is provided on the shank of its sole with a staple 11, (shown removed from the shoe in Fig. 8), the staple being located near enough to the heel to require stretching of the elastic shank of the overshoe to bring the fastening member 8 into engagement.

From the foregoing the method of use will be readily understood. When it is desired to put the rubber sole on the shoe the former is fitted on the leather sole with the flange fitting over the edges of the latter. The fastener 8 is now grasped and pulled backward, thereby stretching the elastic shank of the 110

rubber sole, and the tongue 9 is inserted in the staple 11. Upon release of the fastener the tension of the elastic shank holds the locking members securely in engagement. 5 The rubber sole is thus effectually held against forward movement and consequent disengagement from the leather shoe. When it is desired to remove the rubber, the fastener 8 is drawn back out of engagement 10 with the member 11, whereupon the rubber can easily be detached from the shoe.

In the article illustrated in Figs. 1 to 6, the lip of the flange 3 is inclined downward, as clearly shown in Fig. 5. The object of 15 this construction is to enable one size of overshoes to fit leather shoes of various thicknesses of sole; the downwardly inclined edge of the flange 3 adjusting itself readily to the leather sole whether the same is thick or 20 thin. In the form illustrated in Fig. 6, the edge or lip of the flange 2^a has embedded in it an inextensible cord or wire 12, to prevent stretching and to insure a firm hold on the leather sole when the article is being worn. 25 In Fig. 2 the flange portion 2 is shown integral with a sheet extending across the sole-portion 1, while in Figs. 5 and 6 the said flange 2 is attached by means of a relatively narrow portion extending inwardly under 30 such sheet.

It will be seen that my invention differs radically from any type of rubber footwear previously known. At the same time the invention possesses marked advantages over 35 the prior articles. For example, the leather shoes now commonly worn have much higher heels than formerly, especially in the case of women's shoes, in almost all of which the heels are fully as high as the top of the 40 foot or vamp near the toe. Hence with a low-cut rubber it is not necessary to have it extend around the heel for protection, as a depth of water or mud which would wet above the heel would also wet the front part 45 of the shoe by going over the vamp. Nevertheless, heel parts of some sort were necessary, in order to hold the forward portion of the rubber on the shoe. Moreover, with the so-called "footholds", "invisible overshoes", etc., in which a back strap is provided to hold the forward part in place, it has become a common complaint that the overshoes would not stay on, as the back strap would become stretched after a little 55 use. With my invention, however, which provides means for positively securing the forward part of the rubber to the shoe, all heel parts, back straps, etc., can be dispensed with, thereby materially lessening the cost 60 of the article and making it in every way

more sightly on the foot. Furthermore, the prevailing styles, particularly in women's shoes, vary so much in form of heel that it is practically impossible to produce rubber overshoes which will give a perfect fit; the 65 variation in size, height, length, width, and in the general location of the heel relative to the sole, making a good fit largely if not entirely a matter of mere chance. Thus, leather shoes having the same form or shape 70 of sole may have French, Cuban, military, or regular heels; so that while one rubber might fit any of these shoes on the sole and vamp the same rubber would probably fit only one shoe properly on the heel portion. 75 But with my invention, in which no attempt is made to fit the back of the shoe, the production of well-fitting overshoes is by no means difficult; and that, too, with fewer shapes in lasts. 80

I am aware that it has been proposed heretofore to embed a cord in the vamp or upper of a rubber overshoe, but in every instance such cord has been placed high above the sole of the leather shoe. In my invention, however, the cord is so located as to aid directly in clenching the rubber on the top edge of the leather sole. 85

As previously stated, my invention can be embodied in other forms besides those herein specifically described, and the latter can be modified without departure from the proper scope of the invention. For instance, I do not consider myself limited to any particular type of fastening devices, since there are 95 numerous devices that can be conveniently and successfully used for the purpose. 90

What I claim is:

An article of rubber footwear, comprising a sole-portion devoid of a heel, provided at 100 its edge with an inwardly and downwardly extending flange adapted to readily adjust itself to the edges of shoe-soles of different thicknesses, the shank-portion being elastic and thereby capable of being elongated by stretching, and having secured to it a fastening device to coöperate with a fastening device fixed to the shank of the wearer's shoe when the said elastic shank-portion is 105 stretched to bring the fastening device carried thereby into engagement with the device on the shoe; whereby the said fastening device and the inwardly and downwardly extending flange serve to secure the article on the shoe-sole against displacement 110 in any direction. 115
